(76) Inventors: **Henry Hartsuff; Cyrus French**

Henry Harluff and George French
Sellers, Galvin

The aforesaid referred to as inventors, Seller and making first of
the same containing a description in the words of the said Henry Harluff
and George French themselves of their improvement in the man-
ufacture of Pot ash.

It is all to whom these presents shall come, Known
that the Henry Harluff of Tyre in the County of
Seneca and George French of Oneida in the County of Cayuga
and State of New York, have invented a new and useful im-
provement in the manufacure of Pot ash and that the follow-
ing is an exact description thereof. The improvement consists
in an improved mode of filling the leach tubs in the materials used
in filling the same and in saturating the same whilst filling and ex-
tracting the lye. Therefore, First: In filling the leach tubs in the
bottom of sticks and straw in the usual way, pack down upon this
three inches of slackened lime, then add a layer of about five inches
of ashes, saturate this well with weak lye at boiling heat, in which
common salt has been dissolved in the proportion of about three quan-
tins of a bushel of salt to a bushel of ashes. Then add a layer of
about half an inch of dry slackened lime, spread evenly over the surface
of the ashes, then add another layer of ashes of five inches in thick-
ness as above and saturate in the same way, and so on in alternate
layers of ashes and lime as above, saturated in the same manner for
four and not to exceed five layers of ashes in all. It is intended to
use about one bushel of lime to twelve bushels of good house ashes;
but in case field ashes are used, more lime is necessary, and less salt,
in proportion to the quantity of the ashes. Second: After the ashes &
lime are all in the leach tub and saturated as above, then cold
weak lye in cold water may be used, until the lye is all run off.
It is much better to use weak lye than water, until the strong lye
is all leached out of the ashes. Salt and lime have been used heretofore

in the manufacture of hot soles, but not in the manner and in the pro-
cessing, and with the hot soles by above mentioned. What we claim
as our invention, and not previously known is, the use of dry streaked lime
and ashes in alternate layers, and saturating each layer of ashes with
boiling bracke by sea water common salt having been dissolved by which
the strength of the soles is more perfectly obtained in a shorter
time and with less expense and labor.
